[57] **CLAIM**

The ornamental design for an integrated circuit chip holding device, as shown and described.

DESCRIPTION

FIG. 1 is a front view of my new design of integrated circuit chip holding device;

FIG. 2 is a rear view thereof;

FIG. 3 is a top view thereof;

FIG. 4 is a bottom view thereof;

FIG. 5 is a right side elevational view thereof;

FIG. 6 is a left side elevational view thereof; and,

FIG. 7 is a perspective view thereof taken from the top, front, left side of the device.
